CYLINDER LOCK OPERATING CONNECTION

Edward N. Jacobi, Milwaukee, Wis., assignor to
 Briggs & Stratton Corporation, Milwaukee,
 Wis., a corporation of Delaware

Application December 10, 1947, Serial No. 790,881

8 Claims. (Cl. 70—379)

1

This invention relates to cylinder locks and has more particular reference to locks of the type known as pillar locks.

The main characteristic of pillar locks is that they are provided with an operating shaft projecting from the rear of the lock mechanism and driven by the lock cylinder for the actuation of latch mechanism with which the lock is associated. Frequently it is desirable that the operating shaft be joined with the lock cylinder by a universal jointed connection to accommodate misalignment between the cylinder and the latch mechanism to be actuated; and it is the general object of this invention to provide a pillar lock having an improved universal joint driving connection between the lock cylinder and the operating shaft of the lock.

More specifically it is an object of this invention to provide a pillar lock of the character described wherein the operating shaft of the lock has a relatively wide range of universal motion to accommodate a substantial degree of misalignment between the lock cylinder and the latch mechanism operated by the shaft.

Another object of this invention resides in the provision of a novel coupling element connected between the operating shaft and the lock cylinder of a pillar lock of the character described, by which a substantial degree of universal motion of the operating shaft relative to the lock mechanism is possible.

Still another object of this invention resides in the provision of a highly compact universal joint connection between the lock cylinder and the operating shaft of a pillar lock, which connection is readily detachable upon removal of the lock cylinder from the bore of the casing in which it is journalled and is maintained operative by the lock cylinder when properly secured in the bore.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates one complete example of the physical embodiment of the invention constructed according to the best mode so far devised for the practical application of the principles thereof, and in which:

Figure 1 is a perspective view of the pillar lock of this invention looking at the rear thereof and

2

showing the operating shaft protruding from the rear end of the lock casing;

Figure 2 is a front elevational view of the lock shown in Figure 1 but with the key removed;

5 Figure 3 is a side elevational view of the lock of this invention having portions of the lock casing broken away to illustrate details of the connection between the operating shaft and the lock cylinder;

10 Figure 4 is a plan view of the lock shown in Figure 3 likewise having portions of the lock casing broken away to illustrate the connection between the operating shaft and the lock cylinder;

15 Figure 5 is a perspective view showing the rear end of the lock cylinder and the coupling element separated therefrom and disconnected from the operating shaft;

20 Figure 6 is a sectional view taken through the coupling element of Figure 5 along the plane of the line 6—6;

Figure 7 is a sectional view of the coupling element taken along the plane of the line 7—7 of Figure 5; and

25 Figure 8 is a perspective view of the inner portion of the operating shaft showing the construction thereof.

Referring now more particularly to the accompanying drawing in which like numerals indicate like parts, the numeral 5 represents the casing or mounting sleeve of the lock which serves to rotatably house a lock cylinder 6 in the bore 7 thereof. For the purpose of this invention, it is sufficient to state that the lock cylinder 6 is readily detachably retained in the casing bore by any suitable means well known in the art.

35 If desired, however, the lock casing 5 may be provided with a spring retaining blade 8 shown in Figures 2, 3 and 4, secured at its forward end 9 in suitable slits 10 in the front portion of the

40 casing and having a rearwardly projecting arm 8' received in a longitudinal groove 11 in the casing communicating with its bore 7. The free rear end of the arm 8' is bent inwardly as at 12 out of the groove 11 to project into a circumferential

45 groove 13 in the rear of the cylinder for engagement with the forwardly facing shoulder 13' defining one side of the groove to thus detachably retain the cylinder in the casing bore. To remove the cylinder, it is only necessary to lift the free end 12 of the spring arm by a suitable tool inserted through an aperture 14 in the lock casing to disengage the arm from the groove 13.

50 This structure, though shown and briefly described in this application, forms the subject matter of the copending application of the applicant,

filed December 10, 1947, Serial No. 790,882, now Patent No. 2,480,026, issued Aug. 23, 1949, and is described at greater length therein.

The manner in which the cylinder is locked against rotation and unlocked for rotation by means of a suitable key 15 forms no part of this invention and hence has not been illustrated.

According to the present invention the lock casing 5 extends rearwardly beyond the inner end of the lock cylinder and the rear extremity of the casing is provided with an inwardly directed annular flange 17 having a central aperture 18 therein slightly smaller than the diameter of the bore so as to define a step or shoulder 19 at the inner end of the bore spaced from the rear end of the cylinder.

The operating shaft 20 is preferably substantially square in cross section and has its outer free end 21 formed to engage with latch mechanism (not shown) adapted to be actuated by rotation of the shaft. The inner end of the shaft projects through the aperture 18 in the flange at the rear of the casing and enters the bore 7 to be disposed adjacent the rear end of the lock cylinder.

The operating shaft 20 is drivingly connected with the lock cylinder 6 to rotate therewith by means of a novel coupling element 22 confined in the space between the flange 17 and the inner end of the lock cylinder. The coupling element has a central aperture 23 to receive the inner end of the operating shaft, and spaced apart opposite jaws 24 on the rear of the element engage two opposite sides of the operating shaft at the inner end thereof to provide a rotation transmitting connection between the coupling and shaft.

The operating shaft also has a pivotal connection with the coupling element which cooperates with the jaws 24 for the transmission of rotation from the coupling element to the operating shaft. This pivotal connection comprises axially aligned trunnions 26 projecting outwardly from the sides of the shaft engaged by the jaws with the trunnions received in opposite bearing slots 27 cut into the front of the coupling element at the portions thereof lying immediately forwardly of the jaws 24.

For purposes of assembly, it will be apparent that the coupling element is freely slidable along the operating shaft and that the engagement of the trunnions in the bottoms of the bearing slots 27 limits such relative axial sliding motion between these parts in one direction. It is also important to note that the trunnions mount the operating shaft for pivotal motion relative to the coupling element on an axis normal to the axis of the bore 7 and to the jaws 24, and since the aperture 23 in the coupling element is substantially wide adjacent to the jaws 24 a substantial degree of pivotal motion is afforded the operating shaft relative to the coupling element as indicated in Figures 3 and 4.

The driving connection between the coupling element 22 and the lock cylinder is provided by means of a driving lug 30 projecting centrally from the rear of the lock cylinder and engaged between spaced opposite driving abutments or jaws 31 on the forward portion of the coupling element. These jaws are parallel to one another but are disposed at right angles to the jaws 24 at the protruding rear portion of the coupling element. The outer sides of the jaws 31 are provided with boss-like pads 32 and the edge portions of these pads adjacent to the flange 17 are substantially pointed to provide opposite ful-

crums 33 which are adapted to engage the step or shoulder 19 at the bottom of the bore 7 on a line intersecting the axis of the bore and normal to the axis of the trunnions 26 so as to provide for rocking motion of the coupling element in the bore about an axis at right angles to the pivot axis of the operating shaft.

The rear edge portions 35 of the pads are arcuately shaped and concentric to the fulcrum points 33 and are adapted to ride or rock upon the adjacent flat end surfaces 36 of the lock cylinder. Hence, it will be apparent that the coupling element, though rotatable in the casing bore and capable of rocking motion therein, is confined in the space between the flange 17 and the inner end of the lock cylinder by the boss-like pads 32 on the coupling element.

The coupling element is guided for rocking motion about the fulcrum points 33 by the engagement of the forward extremities of the jaws 31 in recesses 38 in the inner end of the lock cylinder, one at either side of the central driving lug 30. For this purpose it will be noted that the outer edge portions 39 of the jaws 31 are arcuate and concentric to the fulcrum points 33 which define the axis of rocking motion of the coupling element and these arcuate edges of the jaws ride on complementary arcuate surfaces at the bottoms of the recesses 38 in the lock cylinder.

The universal joint thus effected between the operating shaft and the lock cylinder thus enables the shaft to be rotated by the cylinder despite the fact that the shaft may be disposed at a substantial angle to the cylinder axis. It will also be apparent that the operating shaft is restrained against substantially all axial motion relative to the coupling element by the engagement of the trunnions 26 thereon with the bottoms of the bearing slots, and by the proximity of the driving lug 30 on the lock cylinder to the inner end of the shaft.

In assembly, the coupling element is slid on over the free end of the operating shaft and the trunnions 26 thereon engaged in the bearing slots of the coupling element. The two parts thus connected are inserted into the bore of the lock casing from its front end. Thereafter the lock cylinder is inserted into the bore to engage the driving lug on its inner end with the jaws 31 on the coupling element, and the universal joint connection thus established is maintained operative by the spring arm 87 in its function of retaining the cylinder in the casing bore.

From the foregoing description taken in connection with the accompanying drawings, it will be readily apparent that this invention provides a relatively simple and inexpensive yet greatly improved universal joint connection between the lock cylinder of a pillar lock and the operating shaft driven thereby.

What I claim as my invention is:

1. In a lock of the type having a bored casing provided with a lock cylinder rotatable in the front portion of the bore, and having an operating shaft projecting from the rear of the bore to provide for actuation of latch mechanism associated with the lock, a universal joint connection between the operating shaft and the lock cylinder comprising: a coupling element confined in the rear portion of the casing bore between a part on the casing and the inner end of the lock cylinder and guided thereby for rotation in the casing bore and for rocking motion of the coupling element on an axis normal to the axis of the bore; a driving connection between

the lock cylinder and the coupling element whereby rotation of the cylinder is transmitted to the coupling element without interfering with rocking motion of the coupling element in the casing bore; and a connection between the operating shaft and the coupling element constraining the shaft to rotation with the coupling element and lock cylinder but permitting swinging motion of the shaft about an axis normal to the rocking axis of the coupling element and relative to the coupling element as well as pivotal motion of the connected shaft and coupling element about the rocking axis of the latter.

2. In a lock of the type having a bored casing and a lock cylinder rotatable in the front portion of the casing bore, and having an operating shaft projecting from the rear of the bore to provide for the actuation of latch mechanism with which the lock is adapted to be associated: a coupling element in the rear portion of the casing bore connected between the operating shaft and the inner end of the lock cylinder to transmit rotation from the cylinder to the operating shaft; and means on the casing at the rear thereof for holding the coupling element in place within the casing bore and engageable with portions of the coupling element to provide a fulcrum about which the coupling element may rock with the axis of rocking motion of the coupling element normal to the axis of the casing bore.

3. The structure set forth in claim 2 wherein in said coupling element is connected between the operating shaft and the lock cylinder for rocking motion of the shaft and coupling element in unison relative to the lock cylinder with the rocking axis normal to the axis of the cylinder, and for pivotal motion of the shaft relative to the coupling element on an axis normal to the rocking axis of the coupling element.

4. In a lock of the type having a bored casing and a lock cylinder rotatable in the front portion of the casing bore, and having an operating shaft projecting from the rear of the bore to provide for the actuation of latch mechanism with which the lock is adapted to be associated: an inwardly directed annular flange at the rear end of the casing restricting the rear of the casing bore; a coupling element rotatable in the casing bore and confined between said flange and the inner end of the lock cylinder; means on engaging portions of the coupling element to provide a fulcrum about which the coupling element may rock on said flange an axis normal to the axis of the casing bore; interengaging means on the coupling element and the inner end of the lock cylinder providing a driving connection between the cylinder and the coupling element, said driving connection allowing rocking motion of the coupling element relative to the lock cylinder; and means connecting the operating shaft with the coupling element for rotation therewith and for bodily motion of the operating shaft with the coupling element during rocking motion of the latter, said last named connection permitting pivotal motion of the operating shaft relative to the coupling element about an axis normal to the rocking axis of the coupling element.

5. In a lock of the type having a bored casing and a lock cylinder rotatable in the front portion of the casing bore, and having an operating shaft projecting from the rear of the bore to provide for the actuation of latch mechanism with which the lock is adapted to be as-

sociated: an annular flange at the rear end of the casing directed inwardly toward said shaft; a coupling element rotatable in said bore and confined between the inner end of the lock cylinder and said flange on the casing; means on said coupling element engaging the flange to fulcrum the coupling element for rocking motion about an axis normal to the axis of the casing bore; a rotation transmitting connection between the coupling element and the shaft including a slot in the front portion of the coupling element opening to the rear of the lock cylinder, and a pin on the shaft engaged in said slot to provide for pivotal motion of the shaft relative to the coupling element on an axis normal to the rocking axis of the coupling element; and a rotation transmitting connection between the coupling element and the lock cylinder maintained operative despite rocking of the coupling element relative to the cylinder, including a driver on the rear of the cylinder, and spaced apart jaws on the coupling element lying at opposite sides of the pivot axis of the shaft and between which the driver is received to transmit rotation to the shaft through the coupling element.

6. The structure set forth in claim 5 wherein said rotation transmitting connection between the shaft and coupling element includes other spaced apart jaws on the coupling element lying at opposite sides of the rocking axis of the coupling element, and a portion on the adjacent end of the shaft non-rotatably received between said jaws to provide a rotation transmitting connection between the shaft and coupling element independent of the pivotal connection therebetween.

7. In a lock of the type having a bored casing and a lock cylinder rotatable in the front portion of the casing bore, and having an operating shaft projecting from the rear of the bore to provide for the actuation of latch mechanism with which the lock is adapted to be associated: an annular flange at the rear end of the casing directed inwardly toward said shaft; a coupling element slidably on the shaft but non-rotatably received on the inner end thereof, said coupling element being rotatably received in said bore and confined between the casing flange and the rear end of the lock cylinder; opposite fulcrum portions on the coupling element abutting the casing flange to provide for rocking motion of the coupling element about an axis normal to the axis of the bore; opposite trunnions on the inner end of the shaft received in bearing slots in the coupling element opening to the front end of the coupling element to provide for pivotal motion of the shaft relative to the coupling element about an axis normal to the rocking axis of the coupling element, sliding of the shaft inwardly of the bore in a direction to disengage said trunnions from their bearing slots being precluded by the rear end of the lock cylinder; and a rotation transmitting connection between the rear end of the lock cylinder and the coupling element by which rotation of the cylinder is transmitted to the coupling element and the operating shaft despite rocking motion of the coupling element in the casing bore or pivotal motion of the shaft relative to the coupling element.

8. In a lock of the type having a bored casing and a lock cylinder rotatable in the front portion of the casing bore and having an operating shaft projecting from the rear of the bore to

provide for the actuation of latch mechanism, with which the lock is adapted to be associated; an inwardly directed annular flange on the rear end of the casing restricting the rear of the casing bore; a coupling element rotatably received in said bore between the flange and the rear end of the lock cylinder and fulcrummed on said flange for rocking motion about an axis normal to the axis of the bore; interengaging means on the coupling element and lock cylinder cooperating with said flange to guide the coupling element for rocking motion on said axis; a driving connection between the lock cylinder and the coupling element maintained operative despite rocking of the coupling element in the bore; and a connection between the operating shaft and the coupling element providing for pivotal motion of the shaft relative to the coupling element about an axis normal to

the rocking axis of the coupling element and through which rotation of the cylinder is transmitted to the shaft through the coupling element.
